UNITED STATES PATENT OFFICE.

WALTER S. ADAMS, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

BOLSTER GUIDE AND DAMPER.

1,135,483.

Specification of Letters Patent Patented Apr. 13, 1915.

Application filed June 2, 1914. Serial No. 842,399.

To all whom it may concern:

Be it known that I, WALTER S. ADAMS, a citizen of the United States, and a resident of the city and county of Philadelphia and 5 State of Pennsylvania, have invented a new and useful Improvement in Bolster Guides and Dampers, of which the following is a specification.

The object of my invention is to provide 10 a device of this class which will eliminate the necessity of using chafing plates between a truck bolster and the truck transoms, and to provide a means which will prevent the bolster from excessive swinging on its sup- 15 porting links in the direction of its length and transversely of the truck, but which will not prevent it from moving from one position to another, as may be required by the conditions of service. At the present time, 20 bolsters frequently swing too freely, so that the car body which is supported by them is subject to unnecessary transverse vibration. All such vibrations are overcome by my invention, one embodiment of which will be 25 hereinafter more particularly set forth.

For a more particular description of my invention, reference is to be had to the accompanying drawing, forming a part here- 30 of, in which—

Figure 1 is a plan view of a structure embodying my invention; Fig. 2 is a side elevation of the same; Fig. 3 is a sectional view on the line 3—3 of Fig. 1, looking in the direction of the arrows; and Fig. 4 is a sectional view on the line 4—4 of Fig. 1, looking in the direction of the arrows.

Throughout the various views of the drawings, similar reference characters designate similar parts.

The car truck to which my invention can be applied may be of conventional or desired construction, and is provided with side frames 1, transoms 2, said transoms being secured together by a tie bar 3. Gusset plates 4 also secure the transoms to the side frame 1. All of the foregoing is shown in dotted lines on the drawings. The transoms are also connected by a bar *a* which is secured to said transoms by bolts *b*.

A bolster 5, shown in dotted lines, is supported in any suitable way from the frame, so that the bolster 5 can move, in the absence of the mechanism described below, with the usual freedom of movement in the direction of its length. To hold this bolster

free and keep it out of contact with the transoms, and at the same time keep it from moving too freely, mechanism may be used which will now be described.

Any suitable spring or other equivalent means for movably supporting the bolster may be employed, so that it may have the usual vertical and lateral play between the transoms. The bolster shown herein is supported by coil springs 6 and links 7 (shown in dotted lines) said links 7 allowing the bolster to have a swinging movement transversely of itself.

Secured to the bolster 5 by means of bolts 8 are two bearing blocks 9, said bearing blocks being pivoted at their upper ends on a pin 10, the inner end of said pin being reduced at 11 and threaded for the reception of nuts 12. A coil spring 13, having seats 14 is mounted on the reduced portion 11 of the pin 10. On the interior of the bearing blocks 9 at the upper end surrounding the pin 10 are hardened steel bushings 15 to prevent wear. Extending between the two bearing blocks 9 is a bar 16 on top of which 70 is mounted another bar 17 extending horizontally. Extending through said bars is a bolt 18 having a head 19 at its lower end and a reduced portion 20 at its upper end said reduced portion being threaded for the re- 75 ception of nuts 21.

Mounted on the transom 6 are blocks 22, said blocks being secured thereto by means of bolts 23, and extending through said blocks 22 is a pin 24 the inner end of said 90 pin being reduced and provided with spring and nuts in the same manner as the pin 10. Between the blocks 22 is a plate 25 and on said plate rests the bar 17, and extending through said plate 25 and bar 17 is another 95 bolt 18 having head 19, reduced end 20 and nuts 21. Extending between these two bolts 19 is a leaf spring 26. If desired, coil springs may be substituted in place of said leaf spring.

When the parts are assembled as set forth, the nuts 12 and 21 are placed tight enough to force the respective springs under them into close contact with their adjacent parts so that the parts 9 and 17 can move only 105 with considerable friction, the amount of dampening of the movement of the bolster will depend upon the tension which is put upon the respective springs 11 and 26. This dampening device is, of course, duplicated 110

at both ends of the bolster, or at appropriate points along the length of the bolster; and instead of having the dampening devices extending in the same direction, they may 5 extend in directions opposite to each other.

It is clear that my invention may be otherwise embodied as here shown.

Having described my invention, what I claim is:

- 10 1. In a car truck, a bolster, a bearing thereon, a truck frame, a bearing thereon, a bar extending between the said bearings and having pivotal connection therewith, a spring extending between the pivotal connections, and means combined with said pivotal connections for varying the tension of said spring.
- 15 2. In a truck, a bolster, bearing blocks on the bolster, a truck frame and bearing blocks thereon, cross-bars having bearings engaging the bearing blocks, means for imposing frictional resistance on said bearings, a bar extending between said cross bars, pivots connecting the latter bar and said cross-bars, a spring extending between said pivots, and means for regulating the resistance of said springs.
- 20 3. In a car truck, a frame and bolster movably mounted within said frame, bearing blocks on said bolster, a pin in said bearing blocks, a spring on said pin, a link on said pin, a second pin connected to said link, blocks on said frame carrying said last men-

tioned pin, a spring on said last mentioned pin and a spring adjacent to said link, and 35 means for holding said spring adjacent to said link.

4. In a truck, a frame, with a bolster mounted therein, blocks secured to said frame, a pin extending through said blocks, 40 a spring on said pin, bearing brackets secured to the bolster, a pin in said bearing brackets, a spring on said pin, upright bolts on said pin and a spring extending from said bolt to an upright bolt on the pin in 45 blocks secured to the frame.

5. In a car truck, a bolster within said frame, bearing blocks on said bolster, a pivotal bar connecting said bearing blocks, bearing blocks on the truck frame, a bar connecting said bearing blocks, a bar extending from said bar and the bar connecting the bearing blocks on the bolster, upright bolts extending through said bars having heads on their lower ends, reduced portions on their upper ends, a spring extending between said upright bolts and nuts for adjusting the tension of said spring. 55

Signed at the city of Philadelphia, county of Philadelphia, and State of Pennsylvania, 60 this 23rd day of May, 1914.

WALTER S. ADAMS.
